UNITED STATES PATENT OFFICE

GUNNAR EMIL ANDERSEN, OF ELMHURST, ILLINOIS, ASSIGNOR OF TWO-THIRDS TO
JOHN D. MILNE AND ANTON H. TAX, OF CHICAGO, ILLINOIS

CYLINDER BORING MACHINE

Application filed August 4, 1926, Serial No. 126,968. Renewed May 19, 1932.

My invention relates to improvements in cylinder boring machines for internal combustion engines and the like. It has for one object to provide a new and improved form 5 of boring machine which may be mounted on the cylinder casting and may be operated to re-bore the cylinder without removing it from the engine frame and without taking down the engine entirely. Another object is to provide a new and improved form of boring 10 machine which will perform the boring operation smoothly and accurately and wherein any irregularities in contour of the cylinder being bored or treated will have a minimum 15 of effect on the operation of the machine. Other purposes will appear from time to time in the specification.

My invention is illustrated more or less 20 diagrammatically in the accompanying drawings, wherein :

Figure 1 is a vertical section with parts in elevation showing the cutting head in place;

Figure 2 is a vertical section in a plane at right angles to the plane of Figure 1 showing the centering head in place with parts in 25 elevation;

Figure 3 is a section along the line 3—3 of Figure 1;

Figure 4 is a section along line 4—4 of 30 Figure 1;

Figure 5 is a section along the line 5—5 of Figure 2;

Figure 6 is a section through a part of the feed mechanism with parts separated; 35

Figure 7 is a section similar to Figure 6 in a plane at right angles thereto.

Like parts are indicated by like characters throughout.

A is an internal combustion engine cylinder 40 though it will be understood that my invention might be used with any engine cylinder or even to bore out any cylindrical opening whether a part of an engine or not. Projecting upwardly from this engine cylinder are a 45 plurality of studs A¹ which in this case will normally be used to hold the head plug of the engine in place on the axle. A² is a base plate adapted to rest on the engine block. It has a plurality of apertures A³ therein, 50 adapted some of them to be penetrated by the

studs A¹. A⁴ are nuts engaging the studs A¹ adapted to hold the base plate in place on the engine housing. Projecting upwardly from the base plate are a plurality of pads A⁵ from which project upwardly studs A⁶. These 55 pads terminate at their outer corners in lugs A⁷ in which are threaded set screws A⁸. The base plate A² is centrally apertured at A⁹, the aperture being larger in diameter than the maximum diameter of any cylinder to 60 be bored.

Supported on the pads A⁵ is an A-frame B. The lower arms of the A-frame terminate in cross pieces B¹ B¹ terminating in pad engaging apertured feet B², the apertures B⁹ being 65 considerably larger than the studs A⁶. Washers B³ rest on the upper side of the feet B² and nuts B⁴ engage these washers whereby when the nuts are tightened up on the studs the A-frame is locked in place on the 70 base frame. A set screw A⁸ engages each of the feet B² so that these set screws may be used to adjustably position the A-frame with respect to the base plate so as to center the 75 axis thereof in line with the axis of the cylinder to be bored. B⁵ is a sleeve mounted at the lower end of the A-frame in line with the hub B⁶ at the upper end. The hub and the sleeve are both downwardly tapered to contain the segmental bearing sleeves B⁷ which 80 sleeves are tapered on their outside to conform to the taper of the sockets and are cylindrical on their insides. Adjusting screws B⁸ threaded in the sleeve B⁵ and hub B⁶ are adapted to force these segmental 85 sleeves downward to compensate for wear on the inner bearing surfaces.

C is a boring bar or mandrel slidable and rotatable in the bearings B⁷. This mandrel is of different size at the two ends, there being 90 a shoulder C¹ intermediate its ends, at the point where the diameter changes so that the bearing sleeves B⁷ B⁷ are of different size to fit the two different sizes of the mandrel. The lower end of the mandrel terminates in 95 a threaded shank C² on which may be threaded a truncated conical center head C³ or a boring head C⁴, the boring head having diametrically opposed cutting tools C⁵ held in place by set screws C⁶. C⁷ is a collar tightly 100

fitted on the small part of the mandrel and resting against the shoulder C¹. This collar has a lug C⁸ projecting radially therefrom and may be pinned as at C⁹ on the mandrel 5 or if desired be so tightly fitted that no pin is needed.

D is a lead screw parallel with the mandrel and mounted at either end on the A-frame by means of the cap screws D¹ D¹. D² is a 10 ratchet wheel mounted for rotation about the lead screw D. This ratchet wheel has an upwardly extending hub D³ terminating in a solid head D⁴, the solid head being engaged by the segmental threaded members D⁵ which 15 members may be brought into engagement with the lead screw. These members D⁵ are outwardly tapered as at D⁶ and adapted to be engaged by the threaded sleeve D⁷ having a truncated conical socket D⁸ to engage the 20 tapered surface D⁶ and threaded at D⁹ to engage the thread D¹⁰ on the sleeve D³ whereby when the sleeve D⁷ is screwed down the segmental members D⁵ are held in firm engagement with the threads on the lead screw 25 compelling the ratchet wheel to act as a lead nut but when the sleeve is screwed up no longer holding the members against the screw, the ratchet wheel is free to move longitudinally of the lead screw independent of 30 any rotation thereof.

E is a two-part yoke, the two parts of which are held together by the bolts E¹. This yoke surrounds both the mandrel C and the lead screw D, there being one part above 35 the sleeve C⁷ and the other below. The ratchet wheel D² is rotatably mounted in this yoke, one part above and one part below the hub holding it against longitudinal movement with respect to the mandrel so that 40 movement of the lead nut along the lead screw results in identical longitudinal movement of the mandrel in its bearing. Rotation of the collar C⁷ and lug C⁸ causes this lug to engage successive ratchet teeth E² on the 45 ratchet wheel and gradually rotate the nut to longitudinally move the mandrel.

F is a worm housing socketed on the upper end of the A-frame held in place thereon by a set screw F¹. This housing has a removable cover F². The worm wheel F³ is contained within this housing and is feathered at F⁴ to engage a keyway F⁵ in the mandrel. F⁶ is a worm in mesh with the worm wheel F³ adapted to be driven through a pulley F⁷ and belt F⁸ from any suitable source of power so that rotation of the pulley and worm drives the worm wheel, and rotates the mandrel. F⁹ is a hand wheel removably 55 mounted on the end of the mandrel to assist in making adjustment thereof. It may be removed and the worm gear casing and associated parts may be drawn off and a long handle substituted when the mandrel can be operated by hand.

The use and operation of my invention are as follows:

When an engine cylinder is to be bored by the use of my machine the cylinder head is removed, the pistons are drawn from above or below the cylinder as the case may be. The cylinder may or may not be taken from the engine or out of the chassis if it is an automobile cylinder, preferably not.

The base plate of my machine is placed on 75 the cylinder block in the place ordinarily occupied by the cylinder head. The arrangement of holes through the base plate is such that the studs on substantially any standard internal combustion engine block can be 80 passed through some of these holes so that the base plate may be pulled in place on the block substantially concentric with the cylinder. The cutting mandrel is backed off to the upper position and the tapered or truncated conical centering member is screwed 85 into the mandrel in the place ordinarily occupied by the cutting head. The mandrel is then moved down until the centering head centers itself in the bore of the cylinder. 90 Since the frame is movably mounted on the base plate, the frame and the centering member can be moved around until the axis of rotation of the mandrel and therefore of the centering member and the cutting member 95 all coincide with the central axis of the cylinder. 95

This manipulation of the frame with respect to the base plate may be by hand or by the use of the four adjusting screws as indicated. When the parts are centered the four 100 clamping nuts are tightened down to hold the frame rigidly in position on the base place. Then the mandrel is backed off, the centering member is removed and the cutting member put in its place.

If the operation is to be a power operation the pulley on the worm shaft will be driven by a belt from any suitable source of power. It will drive the worm gear and rotate the 110 shaft or mandrel. Once each revolution of the shaft or mandrel the lug on the driving collar on the mandrel will engage the ratchet gear on the lead screw and give it a fractional rotation, thus feeding the mandrel downward a short distance each revolution of the cutting member. As this ratchet gear rotates it carries with it the nut on the fixed lead screw rotating that in and around the screw and pulling the drive member down 120 along the screw, thus carrying the mandrel down. This continues until the mandrel with the drive member has been fed clear through the cylinder block, thereby boring out the cylinder to the desired new dimension. 125

At the end of the excursion the drive will be stopped, the compression nut associated with the split nut on the lead screw will be backed off, thereby permitting the segment 130

placed on the lead nut to back out from the place on the lead screw and the mandrel and the cutting member may be withdrawn upwardly back to the starting position, and the 5 machine may then be set up for the next cylinder.

There are two side bushings, one at the upper and the other at the lower end of the frame in which the mandrel is slidably and 10 rotatably mounted. The mandrel itself is carefully made so that it is straight and so that its diameter does not vary within narrow limits from end to end. These bearings in 15 which the mandrel slides and rotates are split bearings. As shown they are segmental, made up of tapered elements in a tapered bore. The bearing adjustment ring is threaded at the top of the bore and may be rotated to drive the tapered elements into the tapered 20 bore thereby compensating for any wear in the sleeve and thereby making it possible to keep the lateral movement of the mandrel within very narrow limits, and thus making it safe to withdraw the cutting tool back 25 through the work without changing the diameter of the tool.

When it is desired to perform the operation by hand, the housing containing the worm gear and worm is released from the upper end 30 of the frame by releasing the set screw. The hand wheel at the upper end of the mandrel is removed and the worm and housing are raised upwardly off the mandrel. Since the driving connection between the worm gear 35 and the mandrel is by means of a key-way on the mandrel and a spline on the gear, it can easily be done. Then a crank can be put on the end of the mandrel and the mandrel can be rotated by hand. Of course, the cut taken in 40 reboring a cylinder must be very light, otherwise the cylinder would be too big so that it is an operation that can be done by hand.

I claim:

1. In a boring machine, a vertical frame 45 adapted to be supported on the part to be bored, a smooth cylindrical mandrel, spaced bearings in which it is rotatably and slidably mounted, a fixed lead screw on one side of and parallel therewith, a nut rotatably 50 mounted on the screw, and a yoke carrying the nut and being provided with two spaced members engaging separated portions of the nut and having separated spaced openings 55 through which the screw and mandrel pass and held against longitudinal movement with respect to the mandrel and in which the mandrel is rotatably mounted, means interposed between said members whereby ro- 60 tation of the mandrel rotates the nut, means for releasing the engagement of the nut with respect to the screw and the mandrel to permit movement of the mandrel independent of the nut said means simultaneously releas- 65 ing the engagement of the nut with the screw

so that the nut may be moved without rotation longitudinally along the screw.

2. In a boring machine, a smooth cylindrical mandrel, spaced bearings in which it is rotatably and slidably mounted, a fixed lead 70 screw parallel therewith, a nut rotatably mounted on the screw, and a yoke carrying the nut held against longitudinal movement with respect to the mandrel in which the mandrel is rotatably mounted, means as- 75 sociated therewith whereby rotation of the mandrel rotates the nut, the nut comprising a movable threaded segment, a tapered cap adapted to engage the segment to force it into engagement with the lead screw, said 80 tapered cap when backed off automatically releasing the segment from the screw, so that the nut may be moved bodily along the screw without relative rotation thereof.

Signed at Chicago county of Cook and 85 State of Illinois, this 30th day of July 1926.
